UNITED STATES PATENT OFFICE.

ROSCOE C. ZUCKERMAN, OF STOCKTON, CALIFORNIA.

DEVICE FOR SEPARATING POTATOES FROM FLOATABLE FOREIGN MATTER.

Application filed November 1, 1926. Serial No. 145,450.

This invention relates to improvements in potato washing devices, and particularly to one to be used in connection with a potato cleaner of the type shown in my co-pending 5 application for patent, Serial No. 87,223, filed February 10th, 1926. Both machines are particularly intended to handle potatoes grown in peat land, the lumps of which are floatable and a certain number of which be- 10 come unavoidably mixed with the potatoes as the latter are dug, and must of course be separated from the potatoes before the lat- ter are sacked.

The previous machine was originally in- 15 tended not only to cause the lumps to be separated from the potatoes, but also to scrub and wash the potatoes free of any dirt which might be caked thereon. I found from experience however that in order to 20 properly permit the lumps of peat to float out of the tank with the overflow of the water, such water had to be maintained at a very high level so that the revolving drum in which the potatoes were scrubbed was 25 almost completely submerged. The result was that due to the relatively low specific gravity of the potatoes the latter tended to float also while in the revolving drum and did not become properly scoured.

30 The principal object of the present invention is to provide a pre-cleaning apparatus especially intended to initially handle the potatoes before they are passed to the washing and scouring tank, and in which 35 means is provided for enabling the floating lumps to be positively separated from the potatoes and to be impelled toward the over- 40 flow, so that when the potatoes are delivered to said washing tank they are free of such lumps and the water in said tank and re- 45 volving drum may be maintained at a level sufficiently low to enable the washing and scouring operations to be efficiently and completely carried out.

45 A further object of the invention is to provide means for causing the potatoes and lumps of dirt to be delivered into the separating tank over practically the entire length thereof instead of at a single point 50 in such length, as was the case with the previous machine. This eliminates the possibility of a heavy potato resting on top of a piece of dirt, carrying the same down, and preventing such dirt from floating and be- 55 ing carried away.

Another object is to provide means for

causing the floating lumps to be positively conveyed to the overflow independent of the current of the water tending to move the lumps in that direction.

60 A further object of the invention is to produce a simple and inexpensive device and yet one which will be exceedingly effective for the purpose for which it is designed.

65 These objects I accomplish by means of such structure and relative arrangement of parts as will fully appear by a perusal of the following specification and claims.

70 In the drawings similar characters of reference indicate corresponding parts in the several views:

Fig. 1 is a sectional elevation of my im- 75 proved separating device.

Fig. 2 is a fragmentary top plan view of the same.

Referring now more particularly to the characters of reference on the drawings, the numeral 1 denotes a rectangular tank of suitable dimensions whose front end wall 80 2 is lower than the remainder, so as to form an overflow, said wall being provided with a vertically adjustable control gate 3 at the top. The tank has a water intake pipe 4 at the rear end thereof adjacent the bottom, 85 the water normally flowing from this pipe toward and over the gate 3 into a drain chute 5 arranged in connection with the tank at the forward end thereof. To cause the water to be normally deflected upwardly 90 from the intake pipe I mount a perforated baffle plate 6 at the rear end of the tank. This plate has a downward and forward slope from the rear end of the wall of the tank above the pipe 4, and is hinged along 95 its upper end. Upon turning this plate on its hinge so that the lower end is raised, the water will flow directly toward the forward end of the tank. At such end the wall 2 is provided with a vertical and hinged gate 100 7 extending upwardly from the bottom of the tank a certain distance, this gate being adapted to open inwardly toward the drain. The water will then flow directly from the pipe 4 into the drain without passing over 105 the gate 3. This enables the tank to be flushed out when necessary to remove any sediment or the like which may have collected in the bottom of the tank.

110 Positioned in longitudinal alignment with the tank a certain distance ahead of its forward end is a hopper 8 into which the

potatoes and any lumps of dirt which may be mixed therewith are dumped. To lift the potatoes and dirt from the hopper and deliver them to the tank I provide a conveyor structure consisting of endless and transversely spaced chains 9 with transverse and longitudinally spaced slats 10 extending between the chains at intervals. This conveyor, which is preferably continuous from 5 end to end, comprises an upwardly sloping portion A extending from the hopper to a point a short distance above the end wall 2 and a horizontal portion B extending from said end wall toward the rear end of the 10 tank. The chains of course are mounted at their ends on suitable sprocket wheels 11 and intermediate their ends are arranged with direction changing idlers 12. The sprocket wheels 11 at the rear end of the conveyor 15 are driven by any suitable means so that the upper run of said conveyor travels toward the rear end of the tank. Flooring 13 of any suitable character is placed under the upper run of the portion A, while the flooring 20 under the upper run of the horizontal portion B is in the form of a metal plate 14. This plate has a large V-shaped opening 15 cut therein extending from the sides of the plate at its rear end (under the rear end 25 of the conveyor B) toward the opposite end of said conveyor, the apex of said opening being preferably disposed centrally of the width of the conveyor. The result of this 30 construction is that as the potatoes and dirt raised from the hopper by the conveyor move onto the plate under the conveyor B and over the gradually widening opening in said plate, they will drop from between the 35 conveying slats a few at a time into the tank below, since the number of potatoes which can drop at any one point in the length of the conveyor is of course governed by the width of the opening at such point. This causes the discharge of the potatoes 40 and dirt lumps into the tank to be spread over a considerable portion of the length of the tank, as will be evident.

Disposed in the tank is a discharge conveyor which includes a horizontal portion C 45 under the conveyor B, and an upwardly sloping portion D leading from the rear end of the portion C to the rear end of the tank at the top thereof. At its upper end said conveyor discharges onto an apron 16 by means of which the potatoes are fed into the scouring and washing apparatus such as that shown in the co-pending application hereinbefore mentioned. This discharge conveyor, like the feed conveyor, comprises 50 endless chains 17 mounted on suitable sprocket wheels 18 and transverse and longitudinally spaced slats 19 extending between the chains at intervals, the upper runs of both portions of this conveyor having suitable flooring 20 thereunder. This con-

veyor is driven from its upper sprocket wheels 18 so that its upper run moves toward the rear end of the tank.

In operation a constantly changing flow of water is maintained in the tank to a level 70 such that the slats 10 on the lower run of the conveyor B are partly immersed in the water. The relative setting of the slats in the water may be maintained in various ways, as by altering the volume of water entering the tank through the pipe 4; raising or lowering the gate 3 so as to alter the relative volume of the overflow; or by raising or lowering the conveyor B. By reason of the above described features of construction as the dirt and potatoes are fed onto the plate 14 and drop through the opening 15 into the tank, the potatoes continue downwardly until they rest on the lower conveyor, by which they are raised to the top 80 and rear end of the tank. The lumps of dirt however floating on the water are caught by the slats on the lower run of the constantly travelling conveyor B (which lower run is moving toward the forward end 85 of the tank as is the water) and are positively impelled toward the overflow and thence of course into the drain. The opening 15 in the floor plate is so disposed relative to the rear end of the conveyor B that all matter carried by said conveyor will have been discharged into the tank before the rear end of the conveyor is reached. This prevents the possibility of any lumps of dirt 90 possibly being caught and raised out of the water by the conveyor D, which of course must project above the adjacent end of the conveyor B.

To prevent the possibility of any potatoes from dropping onto the floor of the tank 105 between the front end wall 2 and the adjacent end of the conveyor C, a sloping deflector plate 21 extends transversely in the tank above the conveyor and projects from the end wall 2 to a termination overhanging the adjacent end of the conveyor C.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A device for separating potatoes from floatable foreign matter comprising a tank to contain a liquid, an overflow for the liquid at one end of the tank, and a common means for feeding potatoes and foreign matter initially mixed therewith into the tank and 125

- for positively moving such matter toward the overflow while allowing the potatoes to drop through the liquid clear of said matter.
2. A device for separating potatoes from floatable foreign matter comprising a tank to contain a liquid, an overflow for the liquid at one end of the tank, a common means for feeding potatoes and foreign matter initially mixed therewith into the tank and for positively moving such matter toward the overflow while allowing the potatoes to drop through the liquid clear of said matter, and a conveyor for raising the potatoes from the liquid and onto which said potatoes are received after dropping through the liquid.
3. A device for separating potatoes from floatable foreign matter comprising a tank to contain a liquid, an overflow for the liquid at one end of the tank, and a horizontal driven conveyor in the top of the tank; said conveyor including endless members forming upper and lower runs, and transverse slats mounted thereon, said conveyor being adapted to carry a supply of potatoes, together with any floatable foreign matter, and deposit them in the tank; the slats on the lower run of the conveyor depending below the level of the liquid and moving toward the overflow.
4. A device for separating potatoes from floatable foreign matter comprising a tank to contain a liquid, a conveyor to carry potatoes and any floatable foreign matter mixed therewith to the tank, said conveyor extending lengthwise of the tank above the level of the liquid therein, and means arranged in connection with the conveyor for causing the discharge of the potatoes and foreign matter therewith from the conveyor into the tank to be distributed over a considerable portion of the length of the tank.
5. A device for separating potatoes from floatable foreign matter comprising a tank to contain a liquid, a conveyor to carry potatoes and any floatable foreign matter mixed therewith to the tank, said conveyor extending lengthwise of the tank above the level of the liquid therein, and including transversely spaced members with slats extending
- therebetween at intervals, and a fixed floor 50 under the slats, said floor being cut away diagonally from one end and side thereof toward the opposite end and side.
6. A device for separating potatoes from floatable foreign matter comprising a tank 55 to contain a liquid, a conveyor to carry potatoes and any floatable foreign matter mixed therewith over the tank above the level of the liquid from one end of the tank toward the other, said conveyor including transversely spaced members with slats extending therebetween at intervals, and a fixed floor under the slats having a V-shaped opening therethrough extending lengthwise therein from the sides of the floor at the end thereof 60 toward which the conveyor is adapted to travel.
7. A device for separating potatoes from floatable foreign matter comprising a tank to contain a liquid, an overflow for the liquid 70 at one end of the tank, means for discharging potatoes and foreign matter therewith into the top of the tank, a water intake member at the end of the tank opposite to the overflow, a normally closed gate in the overflow end of the tank adjacent the bottom thereof, and means for deflecting the flow of water from the intake member to cause such flow to take place diagonally in the direction of the overflow or horizontally toward 75 the gate.
8. A device as in claim 7, such latter means comprising a perforated baffle plate hinged above the water intake and extending diagonally across the same in the direction of the 80 gate.
9. A device for separating floatable from sinkable matter comprising a tank to contain a liquid, a liquid inlet into the tank, an overflow gate in the tank, and a slotted conveyor 90 to carry the mixed material into the tank, the return runs of the conveyor being adapted to ride the top of the liquid in the tank in the direction of and over the overflow gate to positively carry the floatable 95 material to such gate.

In testimony whereof I affix my signature.
ROSCOE C. ZUCKERMAN.
